HAIR CURLING PAD

Diane Labelle, Gladys Sills, and Joseph Stefano,
Ottawa, Ontario, Canada

Application October 5, 1942, Serial No. 460,910
In Canada October 6, 1941

1 Claim. (Cl. 132—36.2)

The invention relates to improvements in hair curling pads, as described in the present specification and illustrated in the accompanying drawings that form a part of the same.

The invention consists essentially of the novel features of construction as pointed out in the claim for novelty, following an explanation in detail of an acceptable form of the invention.

The objects of the invention are to reduce the cost in the manufacture of pads utilized in hair curling by avoiding the use of expensive covers such as aluminium or tinfoil, and substituting there in place a cover less expensive and more efficient for the purpose and permitting the use of the aluminium or tin, thus saved, for more important manufactured products; to enable hairdressers and others to accomplish a better permanent hair wave than heretofore, due to the fact that the pads may be applied to the hair for a longer period than the ordinary pads using metal foils; to allow the hair to remain moist and soft after the use of the non-metallic pads and minimizing the danger of burning of the hair which occasionally occurs through the use of metallic pads, and also preventing the hair from being dried and brittled and the consequent ruination of the same, which is often the penalty for those persons who have too many permanent waves applied to the hair, and through the use of a non-metallic pad it is immaterial how many permanents a person may have, in fact, the more permanents the better it is for the hair; and, generally, to provide a non-metallic hair curling pad that will be comparatively cheap to manufacture and efficient for its purpose.

In the drawing:

Figure 1 is a perspective view of a non-metallic hair curling pad.

Figure 2 is an end view of the pad.

Figure 3 is a plan view of the cover in its extended position prior to its attachment to the pad.

Figure 4 is a plan view of a modified form of cover.

Like numerals of reference indicate corresponding parts in the various figures.

Referring to the drawing, the non-metallic hair curling pads consist of one or more sheets of absorbent material such as flannelette, as indicated by the numeral 10, and a sheet of wax paper 11 divides the absorbent sheets of material from the non-metallic cover 12. The absorbent material sheets, the wax paper, and the non-metallic cover are secured together along one side 13 by

sewing or other fastening means 14 and, thereby, completing the pad.

The non-metallic cover is formed of an elongated sheet of paper 15, which is treated by a chemical process to make the paper heat-resisting and this paper is preferably treated with a wax sulphite or other standard heat resisting paper procurable on the market. This sheet of paper is simply folded doubly and has its free ends 16 sewn together and to the wax paper and the flannelette sheets, and an additional sheet 17 of heat-resisting paper is inserted between the folds of the elongated sheet of paper and secured thereto.

15 In Figure 4 the non-metallic cover is formed of an elongated sheet 18 having the folding lines 19 and 20 so that by bending this sheet of paper (which is also chemically treated for heat-resisting) over the folds a triple sheet will be formed and one edge of the triple sheet is secured to the wax paper and the absorbent material sheets to complete the pad.

20 The application of the pad to the hair is accomplished in the same manner as those pads having metallic covers, that is to say, the hair is first treated with a suitable solution which is specially prepared for the curling of the hair; the flannelette sheets are dipped into water or other liquid, and the pad is then applied by folding over the rolled portion of the hair and held thereto by means of a clamp which is heated, and the heat derived from the clamp will be transferred through the non-metallic covering to the wax paper and the flannelette sheets and into the hair and, by the use of a non-metallic covering, the heat is conserved for a longer period than would otherwise be the case if it were applied to a metallic covering, and consequently, the hair will not be subjected to a sudden inrush of heat radiation but to a gradual radiation of heat and, thereby, avoiding the danger of the sudden evaporation of the solution from the hair which would have the effect of not only giving an inferior curl to the hair but leave it in a dried and brittled state, because when the solution is heated too rapidly it will not only lose its usefulness in the process of making a proper curl, but it would withdraw, in its evaporation, the natural oils from the hair with deleterious results.

25 In using the non-metallic pad, the solution is gradually heated and exudes a gradual chemical reaction to the hair for forming the curl and, since the heat is not too great, the natural oils which are so important to the hair are allowed to remain, with the result that excellent curls are

formed that are soft and moist and giving a longer permanency to the curl.

We claim:

In hair curling pads, a pad having a plurality of flannelette sheets, a cover made of paper which is treated with heat resisting chemicals, said cover being folded double and having its ends and one side of the flannelette sheets secured to-

gether, and an intermediary heat resisting chemically treated sheet located between the folds of said cover and having one end secured to the fastening portion of said pad.
